UNITED STATES PATENT OFFICE

DAVENPORT BROUSE, OF TORONTO, ONTARIO, CANADA, ASSIGNOR, BY MESNE ASSIGNMENTS, TO SERVICE STATION EQUIPMENT COMPANY, LIMITED, OF TORONTO, CANADA

GASOLINE-DISPENSING APPARATUS

Application filed December 9, 1924. Serial No. 754,866.

The principal objects of the invention are to effect an instantaneous automatic refilling of the measuring bowl following the dispensing of a quantity of the gasoline therefrom, thereby effecting a saving of time and ensuring a greater rapidity of service.

A further object is to entirely eliminate waste in handling the gasoline thereby effecting a direct saving and also eliminating the danger of fire as all overflow is returned to the main supply.

The principal feature of the invention consists in the novel construction and arrangement of parts, whereby the control of the supply of gasoline to the measuring bowl is governed automatically by the manipulation of the dispensing tube.

In the drawings, Figure 1 is a perspective view of a dispensing apparatus showing the arrangement of the measuring standard and supply tanks.

Figure 2 is an enlarged elevational view of the interior mechanism of the dispensing device.

Figure 3 is a further enlarged view of a portion of the automatic control mechanism shown partly in vertical section and in position ready to open the air valve.

Figure 4 is a view of a portion of the mechanism shown in Figure 3 showing the air control valve release mechanism in the releasing position.

Figure 5 is a full size vertical sectional view of the control valve mechanism showing the compressed air supply for elevating the gasoline to the bowl.

Figure 6 is a view similar to Figure 5 showing the air valve opened to direct compressed air to the bowl supply tank.

In the dispensing of gasoline a great variety of "pumps" are used and the present invention has to do with the "visible bowl" type. The form shown is compressed air operated, the gasoline being forced upwardly to the bowl from a small tank of slightly greater capacity than the bowl, said small tank being fed from the main reservoir.

In the construction illustrated, the tank 1 is the main supply and the tank 2 is fed by

gravity from the tank 1 through the pipe 3, a check valve 3^x being arranged therein.

An air pipe 4 leads to the tank 2, being fed from a suitable pressure supply and controlled by a valve mechanism hereinafter described.

When the compressed air is directed through the pipe 4 the gasoline in the tank 2 is forced up through the pipe 5 to the bowl 6.

Some well known forms of pumps have this air supply controlled by a hand operated valve but it is the purpose of this invention to make the control of the air automatic.

In the construction herein shown an overflow pipe 7 extends upwardly within the bowl to the level of the highest graduation mark thereon and when the bowl is filled to this level any further quantity of gasoline entering the bowl spills down the pipe 7 and is conducted to a cylindrical casing 8 which is provided with an enlarged portion 9 in the side walls of which are arranged the ports 10.

A funnel-shaped receptacle 11 is connected to the flanged bottom of the portion 9 and conducts the gasoline flowing thereinto to the pipe 12 which returns to the main tank 1.

Within the cylinder 8 is arranged a piston 13 in the form of a flat plate provided with parallel guiding lugs 14 extending upwardly therefrom to engage the wall of the cylinder in sliding contact.

When the gasoline overflows into the pipe 7 from the bowl it falls upon the piston 13 and immediately depresses same. The piston is connected with a rod 16 extending upwardly through the stuffing box 17 on the top of the cylinder and this rod is connected to a counterbalance lever 18 by a flexible cord 19. The counterbalance of the lever 18 normally holds the piston at the upper end of the cylinder but when the gasoline overflowing into the pipe 7 falls upon the piston, the counterbalance is overbalanced and the piston drops down until the plate enters the enlarged portion 9 when the body of gasoline bearing on the plate flows into the ports 10 and is discharged into the funnel shaped receptacle 11 and instantly clears the piston.

Drain holes 20 are arranged in the piston to allow any gasoline which might otherwise be trapped on top of the piston to escape.

5 A stop member 21 is secured on the rod 16, preferably where it connects with the cord 19.

10 A forked lever 22 having its forked end 23 straddling the piston rod 16 is pivotally suspended from a jaw end 24 on the lower end of a rod 25 which is slidably supported by a bracket 26 which bracket also supports the lever 18.

15 The upper end of this rod 25 is connected to a lever 27 pivotally mounted on a bracket 28, said lever having a fork 29 at its outer end to receive and support the nozzle end of the dispensing tube.

20 The brackets 28 and 26 are supported upon a pipe 30 which connects with the bottom of the bowl and communicates through the T 31 and meter 32 with the flexible dispensing tube 33.

25 A stop valve 34 is arranged below the T 31 and the pipe continues below said stop valve and connects with the drain pipe 12 leading from the overflow from the bowl. This stop valve may be opened to drain out the gasoline from the bowl in the event of fire or when the "pump" is to be left unguarded.

30 Connected to the lower end of the forked lever 22 is a toggle member 35 which is pivotally secured to a T pipe connection 36, the laterally extending portion of which is connected by a flexible tube 38 to the pipe 4 which leads to the elevating tank 2.

35 The toggle member 35 is provided with a laterally extending lug 39 which is engaged by a set screw 40 threaded into a correspondingly arranged lug 41 extending from the lever 22. By the adjustment of this set screw the pivot of the toggle joint 43 between the lever 22 and member 35 is adjusted in its relation to its alignment between the pivotal connection of the lever 22 in the forked supporting member 24 and the pivotal connection of the toggle 35 to the T pipe 36.

40 It will be seen that this adjustment may be made very sensitive so that a very small quantity of gasoline falling upon the top of the piston 13 will break the toggle joint between the lever 22 and member 35 and cause it to assume the position as illustrated in Figure 4.

45 The T connection 36 has secured to its underside a hollow stem 44 which extends into a cylindrical chamber 45. The stem is formed with a flange 46 which slides in the chamber 45 and a tube 47 is secured in said flange and extends through an opening in the bottom wall 49 of the chamber 45.

50 A spiral compression spring 48 encircles the tube 47 and engages the flange 46 exerting an upward pressure to hold the tube in the raised position shown in Figure 5.

55 The tube extension 47 projects into a chamber 50 which is connected by a pipe 51 with

the overflow pipe 12 leading to the main supply tank 1.

60 The bottom end of the tube 47 is adapted when depressed to engage a valve 52 slidably arranged in a recess at the underside of the chamber 50.

65 The valve 52 has a central passage 53 opening through the top and provided with holes 54 opening laterally from the lower end of the stem.

70 A casing 55 is secured to the bottom side of the casing containing the chamber 50 and a rubber or leather gasket 56 is secured between these casings and encircles the stem of the valve 52.

75 The lower end of the stem of the valve 52 is threaded into a valve 57 which is held in contact with the gasket 56 by a coil compression spring 58.

80 The lower end of the casing 55 is connected with a pipe 59 leading from a suitable compressed air supply and is provided with a stop valve 60 by means of which the air may be shut off.

85 In the operation of this device, the gasoline dispensing tube 33, which is connected with the bottom of the bowl in the manner described is normally supported by the forked lever 29 and the toggle joint comprising the forked lever 22 and the toggle 35 is broken as illustrated in Figure 4.

90 When a customer is to be served the valve end of the tube 33 is lifted from the fork and said fork is pulled upwardly by the spring 61, thus straightening the toggle and bringing the forked end of the lever 22 close to the stop 21 of the piston rod 16.

95 When the required amount of gasoline is taken from the bowl the dispensing tube is returned to the lever holder. The weight of the tube and valve swings the lever 27 downwardly pushing down upon the rod 25 against the lever 22 and through the toggle 35 the T pipe 36 with its hollow stem is depressed until the inner end of the extension 47 connects with the valve 52, first making an air tight joint therewith.

100 The valve is then depressed against the pressure of the spring 58 and moves the valve 57 from its seating against the gasket 56. This allows compressed air from the compressed air supply to flow through the hollow stem of the valve 52 and from thence the air flows through the pipe extension 47, hollow stem 44, T pipe connection 36 and flexible tube 38 to the pipe 4 which conducts the air to the tank 2 to elevate the gasoline therefrom through the pipe 5 to the bowl.

105 Upon the gasoline rising to the level of the overflow pipe 7 which is in line with the highest dimension of measurement marked on the bowl, the gasoline flows down the pipe 7 into the cylindrical casing 8 and forces the piston 13 downwardly, bringing the stop 21 into engagement with the fork of

the lever 22 which then swings on its pivot to break the joint of the toggle connection to the air valve. The spring 48 encircling the tube 47 lifts the extension 47 upwardly, first allowing the closing of the air valve 57 and continuing upward it breaks the connection between the valve 52 and the tube 47.

5 The flow of compressed air to the auxiliary supply tank is immediately cut off and the pressure of air in the tank 2 flows back 10 through the pipe 4, tube 38 and tube 47 to the chamber 50 from whence it escapes through the pipe 51 back through the overflow pipe 12 to the main tank 1 which is vented.

15 Immediately following the depression of the piston the overflow is released and returns to the main tank passing through the funnel 11 which allows the rapid escape of the fluid so that the action of the piston will 20 not be impeded. When the overflow ceases the counterweight immediately returns the piston and the device is ready for another 25 operation.

The operation of the device is entirely automatic and is very rapid. The instant the dispensing pipe is hung up the air valve is opened and the supply in the bowl is replenished.

30 It will of course be understood that when the air pressure is applied to the tank 2 the gasoline is prevented from returning to the main tank by the check valve 3*.

The supply pipe 5 leading from the tank 2 to the bowl is provided with a hand operated pump 62 which may be used in the event 35 of the air supply failing.

What I claim as my invention is:

1. In a gasoline dispensing apparatus, the 40 combination with a supply tank, a measuring bowl adapted to receive gasoline from said supply tank, an overflow conduit leading from said bowl, a dispensing tube and means for controlling the lifting of gasoline from the tank to the bowl, of means having 45 a break joint therein and operatively connected with said controlling means adapted to support the dispensing tube and be operated by the hanging of the dispensing tube thereon for actuating said controlling means, and means actuated by the gasoline flowing through said overflow conduit from said bowl for breaking said break joint and rendering ineffective the means for actuating said controlling means.

50 2. In a gasoline dispensing apparatus, the combination with a supply tank, a measuring bowl, a dispensing tube, and means for lifting gasoline from the tank to the bowl, of a movable member for supporting the dispensing tube, a toggle-jointed member connected with the aforesaid movable member, means operated by said tube supporting member through said toggle member for starting said lifting means into operation, and means governed by the overflow from the bowl adapted

to effect the breaking of said toggle joint to arrest the operation of said lifting means.

3. In a gasoline dispensing apparatus, the combination with a supply tank, a measuring bowl, a dispensing tube, and means for lifting gasoline from the tank to the bowl, 70 of a movable member for supporting the dispensing tube, a toggle-jointed member connected with the aforesaid movable member, an overflow pipe leading from the bowl, a cylinder in said overflow pipe, a piston operating in said cylinder and having a stem operatively connected with said toggle jointed member and adapted to break the joint of said toggle member upon the overflow of the bowl, and means operated by the tube supporting member through said toggle member for starting the lifting means into operation.

4. In a gasoline dispensing apparatus, the combination with a supply tank, a measuring bowl, a dispensing tube, and means for controlling the lifting of gasoline from the tank to the bowl, of a movable member for supporting the dispensing tube, a toggle-jointed member operatively connected with the aforesaid movable member and with said lift-controlling means, an overflow pipe leading from the bowl, a cylinder connected at its upper end with said overflow pipe and

receiving the discharge therefrom and having an enlarged lower end formed with a funnel-shaped bottom, a pipe connecting the bottom of said cylinder with the supply tank and forming a continuation of said overflow pipe, a piston in the form of a flat disc having upwardly extending guide lugs slidably engaging the cylinder wall, a rod extending from said piston through the top of the cylinder, a counter balance operatively connected to said piston rod, and means extending from said toggle member operatively engaging said piston rod to break the toggle joint.

5. In a gasoline dispensing apparatus, the combination with a measuring bowl, main supply tank, auxiliary tank, a compressed air supply and a dispensing tube, of a valve closing the air supply to the auxiliary tank, a member adapted to engage and release said valve, said member being normally spring held from engagement with said valve, a lever pivotally mounted for supporting said dispensing tube, a toggle member arranged between and operatively connecting said valve engaging means and said supporting lever,

110 an overflow conduit leading from the measuring bowl, a hollow casing connected with said overflow conduit, a member suspended within said hollow casing and adapted to be depressed by the weight of gasoline passing down said overflow conduit, and means connected with said depressible member adapted to engage and displace said toggle joint to break the operative connection between said support lever and said valve engaging means to permit said valve to close.

115

120

125

130

6. In a gasoline dispensing apparatus, the combination with a measuring bowl, a main supply tank, auxiliary tank, a compressed air supply and a dispensing tube, of a valve closing the air supply to said auxiliary tank, operable means adapted to open said valve, said means including a displaceable toggle-jointed member, means operatively connected with said operable means for actuating the same to open said valve, an overflow pipe leading from the measuring bowl, a cylinder casing connected with said overflow pipe, a piston in said cylinder casing, a rod connected with the piston and extending beyond said cylinder casing, a counterbalance arm connected with said rod, a member on said piston rod adapted to engage and displace said toggle-jointed member to break the toggle joint in said operable means to render the latter ineffective and permit thereby the closing of said air valve upon the depression of the piston, and means for releasing the pressure from the auxiliary tank on the closing of said valve.
7. In a gasoline dispensing apparatus, the combination with a measuring bowl, main supply tank, auxiliary tank, a compressed air supply and a dispensing tube, of a pivotal lever adapted to support the dispensing tube, a rod connected to said lever, a toggle member connected to said rod, a casing adapted to be connected with said compressed air supply, a valve controlling the flow of compressed air to said casing from the supply, a flexible tubular connection to the auxiliary tank connected with said valve and adapted to conduct compressed air from the latter to the auxiliary tank on the opening of the valve and to be disconnected from said air supply upon the closing of the valve, and a conduit leading from the interior of said casing adapted on the closing of the valve to conduct the return flow of air from said flexible tubular connection to the main supply tank to release the air pressure thereinto from the auxiliary tank.
8. In a gasoline dispensing apparatus, the combination with a measuring bowl, main supply tank, auxiliary tank and a compressed air supply, of a valve closing said compressed air supply, a hollow casing arranged above said valve, a tube leading from said casing interior to the main supply tank, a conduit connected to the auxiliary tank and adapted to be extended through the casing interior above the air valve and to connect with said air valve to open the same and to conduct the air pressure from the valve to the auxiliary tank, means for moving said conduit to open said valve, and automatic means for closing said valve and removing said conduit from engagement therewith.
9. In a gasoline dispensing apparatus, the combination with a measuring bowl, a main supply tank, auxiliary tank and a compressed air supply, of a valve casing having an opening at the top, a gasket arranged in said opening, a valve adapted to seat against said gasket, a spring normally holding said valve in its seated position, a tubular valve member secured at one end in the aforesaid valve and extending through said gasket and having a concentric seat in the other end, a casing arranged above said gasket and enclosing the upper end of the tubular valve and having an exhaust opening, a tubular member slidably supported in said upper casing and adapted to engage the seat on the end of the tubular valve member, spring means for moving said tubular member out of contact with the seat on the tubular valve member, a tube connected with said spring-actuated tubular member and leading to the auxiliary tank to conduct the air pressure thereto, means for moving said tubular member into seating engagement with the seat on said tubular valve to unseat said first-mentioned valve, and means for automatically removing said tubular member from engagement with the seat on said tubular valve member to permit the first-mentioned valve to seat and to effect the communication of the upper casing interior with the auxiliary tank through the interior of said tubular member.
10. In a gasoline dispensing apparatus, the combination with a measuring bowl, main supply tank, auxiliary tank, a compressed air supply, a gasoline supply pipe leading from the auxiliary tank to the measuring bowl, and an overflow pipe leading back to the main tank, of a hollow casing interposed in the overflow pipe, an air valve controlling the flow of pressure to the auxiliary tank, means adapted to be operated to open said air valve, means operatively connecting said valve opening means with said valve, said connecting means being operable independent of said valve opening means to effect the closing of said valve independent of the latter, a member arranged in said hollow casing and operated by the overflow and co-operating with said independently operable connecting means to effect the independent operation of the latter, and means for automatically releasing the pressure in the auxiliary tank following the independent operation of said connecting means.
